(57) **CLAIM**

The ornamental design for a smart band for automobile, as shown and described.

DESCRIPTION

FIG. 1 is a perspective view of a smart band for automobile according to the present invention.

FIG. 2 is a front view of the smart band for automobile shown in FIG. 1.

FIG. 3 is a rear view of the smart band for automobile shown in FIG. 1.

FIG. 4 is a left-side view of the smart band for automobile shown in FIG. 1.

FIG. 5 is a right-side view of the smart band for automobile shown in FIG. 1.

FIG. 6 is a top plan view of the smart band for automobile shown in FIG. 1; and,

FIG. 7 is a bottom plan view of the smart band for automobile shown in FIG. 1.

Broken lines in FIGS. 3, 6 and 7 illustrate portions of the smart band for automobile and form no part of the claimed design.

1 Claim, 7 Drawing Sheets
